(74) Attorney, Agent, or Firm — Rumit Ranjit Kanakia

(57) **CLAIM**

I claim the ornamental design for an earphones holder, as shown and described.

DESCRIPTION

FIG. 1 is a Perspective view of an earphones holder showing my new design;

FIG. 2 is a Front view thereof;

FIG. 3 is a Back view thereof;

FIG. 4 is a Top view thereof;

FIG. 5 is a Bottom view thereof;

FIG. 6 is a Left-side view thereof; and,

FIG. 7 is a Right-side view thereof.

1 Claim, 6 Drawing Sheets(56)
